US0D1009623S

(12) United States Design Patent (10) Patent No.: US D1,009,623 S
(45) Date of Patent:  Jan. 2, 2024

(54) CARDBOARD BOX

(71) Applicant: Peter Ammann, Oberhofen (CH)

(72) Inventor: Peter Ammann, Oberhofen (CH)

() Term: 15 Years

(21) Appl. No.: 35/514,435

(22) Filed: Dec. 14, 2021

(80) Hague Agreement Data

Int. Filing Date: Dec. 14, 2021

Int. Reg. No.: DM/218368

Int. Reg. Date: Dec. 14, 2021

Int. Reg. Pub. Date: Jun. 17, 2022

(51) LOC (14) Cl. 09-03

(52) U.S. Cl.

USPC D9/432

(57) CLAIM

The ornamental design for a cardboard box, as shown and described.

DESCRIPTION

1. Cardboard box

1.1 : Front

1.2 : Left

1.3 : Bottom

1.4 : Perspective

1.5 : Back

1.6 : Perspective

1.7 : Right

1.8 : Top

1.9 : Bottom

1.10 : Left

1.11 : Front

1.12 : Perspective

1.13 : Back

1.14 : Perspective

1.15 : Right

1.16 : Top

1 Claim, 16 Drawing Sheets
